UNITED STATES PATENT OFFICE.

HYMAN MAIMIN, OF NEW YORK, N. Y.

SUPPORT FOR SEWING-MACHINE MOTORS.

1,377,017.

Specification of Letters Patent.

Patented May 3, 1921.

Application filed December 8, 1919. Serial No. 343,215.

To all whom it may concern:

Be it known that I, HYMAN MAIMIN, a citizen of the United States, residing at New York city, in the county of New York, State of New York, have invented certain new and useful Improvements in Supports for Sewing-Machine Motors; and I do hereby declare the following to be a full, clear, and exact description of the invention, such as will enable others skilled in the art to which it appertains to make and use the same.

This invention relates to brackets for supporting upon the frames of sewing machines the small electric motors now provided for driving the machines.

In my copending application, Serial No. 337,643, filed November 13, 1919, I have shown a bracket particularly adapted for this purpose, which consists primarily of a supporting member adapted to be brought into engagement with the horizontal arm of the frame of a sewing machine and held in place by the weight of the motor which is mounted upon the free end of the member. In order more securely to hold the supporting member in place, there is associated with the member a locking member also adapted to engage the horizontal arm of the machine frame and arranged to be connected to the supporting member in such a manner as to prevent any displacement of the latter, due to vibration of the motor, or by an upward thrust tending to lift the motor and thus release the locking member. The motor may be attached to the supporting member in such relation to the driving wheel of the sewing machine that a friction pulley on the shaft of the motor will be held in engagement with the driving wheel by the weight of the motor, or a belt may be used for connecting the motor to the driving wheel, the tension of the belt being maintained by the weight of the motor or the elasticity of the supporting member.

By mounting the motor upon a member which is constructed to be secured to the frame of the machine, I avoid the use of pedestals or other supporting members mounted upon the table of the machine, and which are an obstruction and interfere with the use of the table for holding the work. The bracket is on one side of the frame where it is out of the way of the thread, and may be quickly applied to any form of sewing machine without requiring any

preparations, such as the drilling of holes in the frame, or special adjustments. By mounting the motor so that it may be held in operative relation to the machine wheel 60 by its own weight, the use of springs or other devices commonly employed in arrangements of this character is avoided, and the construction of the device is correspondingly cheapened and simplified. 65

In the device of my prior application, one end of the locking member is pivotally attached to the supporting member near the end of the latter which engages the machine frame, and the other end of the locking member is arranged to be clamped to the supporting member at an intermediate point. Sewing machines of the usual construction are provided with spindles projecting from the top of the frame and adapted 70 to hold the spools of thread which are to be used in the machines. In accordance with the present invention, I make use of this spool spindle for retaining in place upon the top of the machine frame an auxiliary 75 supporting member which is associated with the main supporting member at an intermediate point and takes the place of the locking member of my prior application. This auxiliary member may be formed integrally 80 with the supporting member, or it may consist of a separate member adapted to be connected to the supporting member in any convenient manner, as by being provided with a hook in which the supporting member 85 may be seated.

The particular nature of the invention, as well as other objects and advantages thereof, will appear more clearly from a description of certain preferred embodiments as shown 95 in the accompanying drawings, in which—

Figure 1 is a side elevation of the frame of a sewing machine with one form of device in place thereon;

Fig. 2 is an end view of the frame and 100 device;

Fig. 3 is a detailed view of the auxiliary supporting member of the device shown in Fig. 1;

Fig. 4 is a view similar to Fig. 1, but 105 showing a different form of device; and

Fig. 5 is a similar view showing another form of device.

In the drawings, 10 represents the base of a sewing machine frame, comprising a vertical standard 11 and a horizontal arm 12, upon the top of which is mounted a spindle

13 to hold a spool of thread to be used in the machine. At the outer end of the horizontal arm 12 is a head 14 within which the mechanism for reciprocating the needle is 5 mounted, this mechanism being driven by a wheel 15 adapted to coöperate with a friction pulley 16 on the shaft of a small driving motor 17. The motor casing is provided with lugs 18 by which it may be attached to 10 lugs 19 of a supporting member 20 by means of a pin 21, or in any other suitable manner.

The inner end of the supporting member is provided with upper and lower extensions 22 and 23, respectively, adapted to fit 15 over the top and bottom of the horizontal arm 12 of the frame. The supporting member 20 is bent outwardly as indicated in Fig. 2, to clear the machine wheel 15 and bring the pivotal connection for the motor in 20 proper relation to this wheel.

In a supporting member constructed as above described, the weight of the motor upon the end of the member will produce a turning moment which will be opposed by 25 the engagement of the upper and lower extensions with the frame, so that the member may be held in place upon the frame without any other means. In practice, however, I prefer to provide an auxiliary supporting 30 member 24 to coöperate with the main supporting member in holding it more securely upon the machine frame and preventing displacement or dislodgment due to the vibration of the motor, or from any other cause. 35 In accordance with the present invention, this auxiliary supporting member consists of a strip of metal or other suitable material having a flat upper portion adapted to be seated upon the top of the machine frame 40 and provided with apertures 25, through any one of which the spindle 13 may be passed. The depending portion of the strip is turned upwardly as at 26, thus forming a hook within which the main supporting 45 member 20 may be received as shown most clearly in Fig. 1.

When it is desired to apply to the frame of a sewing machine the form of device described above, the auxiliary member 24 will 50 be placed over the spool spindle 13 and the main supporting member 20 will be placed upon the horizontal arm of the frame by tilting it upwardly so that the extensions 22 and 23 may be passed over the top and bottom of 55 the frame, after which the member will be swung downwardly into the position indicated in Fig. 1 until the extensions 22 and 23 engage the frame. The auxiliary supporting member will be so constructed and 60 mounted upon the frame that when the main supporting member 20 is in position, it will enter the hook of the auxiliary supporting member and rest upon the bottom thereof. When the device is properly positioned upon 65 the frame, the motor may be swung about

its pivot 21 to bring the friction pulley 16 into engagement with the driving wheel 15 of the machine.

In the embodiment of the invention described above, it is intended that the bracket 70 shall be so arranged that when it is in place upon the frame of the machine, the motor will be held by gravity with its driving pulley in engagement with the driving wheel of the machine, but as shown in my copending application referred to above, the motor may be suspended from the bracket and its shaft may be provided with a pulley connected by means of a belt to the usual driving pulley on the shaft of the machine. 80 With such a modification, the parts should preferably be arranged so that the motor is drawn toward the pulley of the machine to cause the weight of the motor to maintain the required tension in the belt. As a further 85 modification of the apparatus, the motor may be rigidly attached to the supporting member 20 and the driving belt may be of such length that the motor and the free end of the supporting member will be drawn 90 slightly toward the pulley of the machine so that the resiliency of the supporting member will maintain sufficient tension in the driving belt.

The form of device shown in Fig. 1 may be 95 modified by eliminating the upper extension 22 and employing the auxiliary member to resist the turning moment, due to the weight of the motor. In Fig. 4 there is shown such a modification of the invention in which the 10 supporting member 20' is provided with a single extension 23' adapted to engage the bottom of the horizontal arm of the machine frame. The auxiliary supporting member 24' is of substantially the same construction 11 as that described above, but its hook portion may be provided with apertures adapted to receive a pin or bolt 27 which may pass through any one of a number of apertures 28 in the supporting member 20'.

In the device described above the weight of the motor acting upon the end of the supporting member 20' tends to produce a turning moment which is opposed by the joint effect of the extension 23' and the auxiliary 11 supporting member 24', so that the latter performs in part the function of the upper extension 22 of the embodiment shown in Fig. 1, and also prevents sidewise displacement of the bracket, due to shocks or vibrations of the motor.

The modification shown in Fig. 4 may be further simplified by forming the main and auxiliary supporting members of the bracket out of one piece as shown in Fig. 5. In this 12 case the supporting member 20'' is provided at its inner end with an extension 23'' adapted to engage the bottom of the horizontal part of the machine frame. At an intermediate part of the member there is an up- 13

wardly extending portion 24" which is bent over and provided with apertures through which the spool spindle may be passed. This modification of the device lacks the adjustability of the structure of Fig. 4, but may be advantageously employed in those cases where the bracket is intended to be applied to a particular type of sewing machine, so that it is not necessary to provide for variations in the size and proportions of the frame of the machine.

While certain preferred embodiments of the invention have been shown and described, it will be understood that the invention may be embodied in other forms, and that various other changes in the details of construction may be made without departing from the principle of the invention as defined in the appended claims.

I claim:

1. The combination with the frame and wheel of a machine to be driven, of a motor, a bracket adapted to be detachably secured to a horizontal part of the machine frame and provided at one end with an extension to engage the bottom of this part of the frame, and at an intermediate point with an adjustable member adapted to engage the top of the horizontal part of the frame, means for attaching the motor to the other end of the bracket, whereby its weight will hold the bracket in place on the frame, and means for driving the machine wheel from the motor.

2. The combination with the frame and wheel of a machine to be driven, of a motor, a supporting member adapted to be detachably secured to a horizontal part of the machine frame and provided at one end with upper and lower extensions to engage the top and bottom of this part of the frame, means for attaching the motor to the other end of the member whereby its weight will hold the member in place on the frame, auxiliary supporting means for the member associated with the latter at an intermediate point and provided with an extension adapted to rest upon the top of the horizontal part of the frame, and means for driving the machine wheel from the motor.

3. In a sewing machine having a driving wheel and a frame provided with a spool spindle projecting from the top thereof, the combination of a motor, a bracket adapted to be detachably secured to a horizontal part of the machine frame and provided at one

end with an extension to engage the bottom of this part of the frame, and at an intermediate point with a member adapted to engage the top of the horizontal part of the frame and fit over the spool spindle thereon, means for attaching the motor to the other end of the bracket, and means for driving the machine wheel from the motor.

4. In a sewing machine having a driving wheel and a frame provided with a spool spindle projecting from the top thereof, the combination of a motor, a supporting member adapted to be detachably secured to a horizontal part of the machine frame and provided at one end with upper and lower extensions to engage the top and bottom of this part of the frame, means for attaching the motor to the other end of the member whereby its weight will hold the member in place on the frame, auxiliary supporting means for the member connected to the latter at an intermediate point and provided with an extension adapted to fit over the spool spindle and rest upon the top of the horizontal part of the frame, and means for driving the machine wheel from the motor.

5. A bracket for supporting a motor upon the frame of a sewing machine provided with a spool spindle projecting from the top thereof, comprising a member upon the outer end of which the motor is mounted and provided with an extension adapted to engage the under side of the frame, and means associated with the member and adapted to engage the top of the frame and be held in place by the spool spindle whereby the turning moment due to the weight of the motor is opposed and the member is held upon the frame.

6. In a sewing machine having a driving wheel and a frame provided with a spool spindle projecting from the top thereof, the combination of a motor, a bracket adapted to be detachably secured to the machine frame and comprising a pair of connected members formed at their ends to engage the frame, one of said members being provided with a plurality of apertures adapted to receive the spool spindle to hold the member in place on the frame, means for mounting the motor on the bracket, and means for driving the wheel of the machine from the motor.

In testimony whereof I affix my signature.

HYMAN MAIMIN.
